UNITED STATES PATENT OFFICE.

WILLIAM F. MOSS, OF FITZPATRICK'S, ALABAMA.

COTTON-PRESS CLAMP.

SPECIFICATION forming part of Letters Patent No. 372,862, dated November 8, 1887.

Application filed April 12, 1887. Serial No. 234,515. (No model.)

To all whom it may concern:

Be it known that I, WILLIAM FRANCIS MOSS, of Fitzpatrick's, in the county of Bullock and State of Alabama, have invented a new and 5 Improved Cotton-Press Clamp, of which the following is a full, clear, and exact description.

This invention relates to cotton-press clamps, the object of the invention being to provide a clamp which may be quickly and easily manipulated, and which, when in position to lock the doors of the press together, will not be liable to accidental displacement.

Reference is to be had to the accompanying drawings, forming a part of this specification, 15 in which similar figures of reference indicate corresponding parts in both the views.

Figure 1 is an end view of a portion of a press, representing the same as provided with my improved form of clamp; and Fig. 2 is a 20 plan view of the parts illustrated in Fig. 1.

In the drawings, 10 represents the bottom of a pressing box, 11 the end doors, and 12 the side doors. These side doors, as usual, extend beyond the edges of the end doors, and are 25 provided with cleats 13, against which the end doors rest. The clamps, which are shown at 14, are connected to the upper part of these outwardly extending portions of the side doors, each clamp consisting of a fixed section, 2, which is provided with a shank, 3, that extends through the side door and is engaged by a nut, 4, the movable sections of the clamps being shown at 5 and being connected to the fixed portions 2 by pivot-pins or bolts

6. These movable sections are formed with 35 hooked ends 7, and in applying the clamps, which are arranged in pairs, care must be taken so that these hooked points will extend in inverse directions, in order that they may interlock, as represented in Fig. 1.

In operation it will be seen that the end doors are first closed in, then the side doors, and the hooks of the clamps are engaged as represented in the drawings, when, after the pressing has been completed, a slight knock 45 or kick will separate the hooks, and the side doors will fall outward to allow for the withdrawal of the bale.

Having thus fully described my invention, I claim as new and desire to secure by Letters 50 Patent—

1. In a cotton-press clamp, the combination, with the side doors, of the hooked sections connected to said doors and having hooked ends or points extending in inverse directions, 55 permitting the same to interlock, substantially as and for the purpose set forth.

2. In a cotton-press clamp, the combination, with the side doors, of the hooked sections connected through fixed sections to said doors 60 and having hooked ends or points extending in inverse directions, permitting the same to interlock, substantially as and for the purpose set forth.

WILLIAM F. MOSS.
